CANTILEVERED DESK AND MULTIPLE SHELF COMBINATION

Juan M. del Castillo, Salamanca 34, 2nd Floor,
Mexico City 7, Mexico

Filed Nov. 7, 1973, Ser. No. 413,660

Term of patent 14 years

Int. Cl. D6—03

U.S. Cl. D6—128

FIG. 1 is a perspective view of my cantilevered desk and multiple shelf combination;

FIG. 2 is a rear elevation thereof;

FIG. 3 is a side elevation thereof; and

FIG. 4 is a bottom plan view thereof.

I claim:

The ornamental design for a cantilevered desk and multiple shelf combination, as shown.
